UNITED STATES PATENT OFFICE.

FREDERICK R. PARKER, OF CHICAGO, ILLINOIS.

ELECTRICAL PROTECTOR.

1,252,942.

Specification of Letters Patent.

Patented Jan. 8, 1918.

Original application filed August 20, 1904, Serial No. 221,519. Renewed January 19, 1917, Serial No. 143,414. Patent No. 1,238,728. Divided and this application filed July 18, 1917. Serial No. 181,242.

To all whom it may concern:

Be it known that I, FREDERICK R. PARKER, a citizen of the United States of America, residing at Chicago, in the county of Cook 5 and State of Illinois, have invented a new and useful Electrical Protector, of which the following is a specification, reference being had to the accompanying drawings, illustrating same.

10 This application is a division of my co-pending United States patent application Serial No. 143,414, filed January 19, 1917, which is a renewal of application Serial No. 221,519, filed August 20, 1904.

15 My invention relates to electrical protective apparatus, such as is used for protecting electrical circuits and apparatus of various characters from electricity injurious thereto.

20 The principal objects of my present invention are, to provide an improved electrical protector of the character herein set forth; to provide an improved arrangement of the high-potential electricity arresters in such a protector, and an improved ground plate or mounting plate or means for maintaining the arresters in their improved arrangement. Other objects will be apparent from the following specification.

25 The figure of the drawing is an end view of a strip of my improved electrical protectors, with one of the high-potential electricity arresters shown in cross-section.

30 In protective apparatus of the general character herein disclosed, it has always been difficult to remove the high-potential electricity arresters or lightning arresters from the apparatus by hand, on account of the rows of arresters on opposite sides of the ground plate or mounting plate being located very close to each other, generally a distance apart equal to one or two thicknesses of a thin sheet-metal ground strip.

35 In the protector of this present invention, however, the rows of high-potential electricity arresters are separated a considerable distance from each other, due to my improved construction of the ground plate or mounting plate, so that in removing an 40 arrester from the apparatus the end of the finger may be inserted between the arresters of a pair to enable the arrester which is being removed to be readily grasped between the thumb and finger for removal. Thus, 45 my improved construction entirely elimi-

nates the aforesaid difficulty heretofore experienced in removing arresters from this class of protective apparatus.

In the drawing, which illustrates one form of my present invention, *dd* is a 50 ground plate, of any suitable length to accommodate any desired number of pairs of the protective apparatus. *k*, shows a ground connection for the ground plate *dd*. The body portions *d*, *d*, of the ground plate 55 are preferably of sheet metal and are preferably placed together broadsidedly as shown, although I do not wish to limit this invention to this particular construction. The front portions *d*, *d*, of the portions 60 *d*, *d*, of the ground plate are preferably formed outwardly or spread away from each other as shown, to separate the opposite high-potential electricity arresters from each other as will be hereinafter more fully 65 set forth. The portions *d*, *d*, may be springy portions if desired.

The ground plate *dd* is also utilized as a mounting plate for the apparatus. Spring members *e*, *e*, *f*, *f*, are mounted in rows 70 along opposite sides of the plate *dd*, preferably as shown, by rows of mounting bolts *h*, *l*, the spring members being insulated from each other and from the ground plate *dd* at their mounting by insulation *m*. The 75 spring tension in springs *e*, *e*, *f*, *f*, tends to throw their free ends toward the ground plate *dd*. Opposite spring members *e*, *e*, on respective sides of the mounting plate *dd*, form a pair, as likewise do opposite spring 80 members *f*, *f*, on respective sides of the plate *dd*. In telephone systems, terminals 1 and 2 of each pair of spring members *e*, *e*, are preferably connected with conductors leading to the switchboard, and terminals 3 85 and 4 of each pair of spring members *f*, *f*, are preferably connected with conductors leading to the outside lines.

90 Each set of spring members *e*, *f*, on both sides of the ground plate *dd*, is equipped with a high-potential electricity arrester *a*, *p*, *b*, removably inserted between the outer end *e*, of spring *e* and a portion *d*, of the ground plate, each arrester comprising 95 suitable electrodes *a*, *b*, of carbon, graphite, or some other suitable material, separated by a thin dielectric member *p* of suitable insulating material. The portions *d*, *d*, may consist of series of tongue portions 100 fitting into grooves *a*, *a*, in the respective 105 110

electrodes b_4 b_4 of the arresters, or they may be continuous portions bearing against the backs of the arresters of the respective rows. Thus the arresters a_4 p b_4 , a_4 p b_4 5 are mounted in rows on opposite sides of the ground plate dd , preferably along one edge thereof as shown, the opposing arresters forming pairs. The portions d_2 d_2 of the ground plate separate the arresters a_4 p b_4 , a_4 p b_4 of the respective rows from each other sufficiently to admit the end of 10 a person's finger between opposing arresters of the respective rows, to enable the arresters to be readily removed from the apparatus by hand as hereinbefore stated.

Each electrode a_4 is provided with a lever i_3 pivoted between ears h_4 h_4 of a pin h_3 which is rigidly secured within a hole in the end of a_4 . The lever i_3 is normally 20 soldered between the ears h_4 h_4 by easily-fusible solder. When the apparatus is set for operation the free end of spring f_3 is engaged with one end of the lever i_3 , preferably as shown, the spring f_3 tending to 25 spring to the ground plate dd . The portion e_2 of spring e engages the electrode a_4 near one end thereof so as to place the body of a_4 in a series circuit with springs e and f_3 . a_4 , being of carbon, graphite, or some 30 other suitable resistance material, constitutes a resistance heater and is utilized as such to control the operation of the lever i_3 and thus provide an electrothermally-operable device or sneak-current protector.

35 When a current slightly in excess of the normal, or a larger current, traverses the resistance heater a_4 for a sufficient length of time, such current generally coming from a line conductor and traversing a line spring 40 f_3 , lever i_3 , heater a_4 and switchboard spring e , it produces sufficient heat in a_4 to cause the latter to heat the pin h_3 sufficiently to 45 soften the heat-susceptible material holding the lever i_3 against operation, and thus permit the spring f_3 to operate the lever i_3 from the position i_3 to the position i_4 and release 50 itself from i_3 and spring to the position f_4 against the ground plate dd . This operation opens the main circuit through the 55 heater a_4 and grounds the line spring f_3 , thus protecting the switchboard circuit and apparatus connected with the terminal 2 (or 1) from the abnormal current and also 60 grounding the line. When the heat-susceptible material cools it resolders the lever i_3 to the portions h_4 h_4 in the position i_4 .

When a high-potential current or charge 65 of electricity, such as lightning or other high-potential electricity, comes in from the line over a line spring f_3 , it passes through spring f_3 , lever i_3 , a portion of electrode a_4 , arcs through or across the dielectric p , and passes through electrode b_4 and ground plate dd to ground, thus being diverted 70 from the aforesaid switchboard circuit and

apparatus by the arrester and consequently being prevented from injuring the apparatus connected with terminal 2 (or 1). If the discharge through the arrester a_4 p b_4 continues, or if it is of large volume and short duration, the heat of the arc will heat the electrode a_4 sufficiently to cause the latter to heat the pin h_3 enough to soften the heat-susceptible material holding the lever i_3 against operation, as hereinbefore 75 stated, thereby permitting the spring f_3 to operate the lever i_3 to the position i_4 , as above described, and release itself from i_3 and take the position f_4 against the ground plate dd . This operation opens the main 80 circuit between the springs f_3 and e and grounds the line spring f_3 , as above set forth, thereby further protecting the aforesaid switchboard circuit and apparatus from the high-potential current and also 85 grounding the line. This operation of spring f_3 also stops any arc in the arrester and the consequent heating thereof. In this case also, when the heat-susceptible material 90 cools it resolders the lever i_3 to the portions h_4 h_4 in the position i_4 .

In any case, after the operation of spring f_3 as above described, the protector may be 95 reset for another operation by simply removing the parts a_4 p b_4 from the apparatus, turning the portion a_4 with the lever i_3 half way around so as to bring the other end of lever i_3 into an engaging position for the spring f_3 , and then reinserting the parts a_4 p b_4 into the apparatus to the position 100 shown, at the same time reengaging spring f_3 with the said other end of the lever i_3 in the position shown. The operation and resetting of the apparatus, as above described, may be repeated as many times as 105 desired.

Contact members of a testing plug may be 110 inserted between the ends of e_2 and a_4 , and between the ends of d_2 and b_4 , in either one or both of a pair of protectors, to separate 115 the contacting portions e_2 a_4 and d_2 b_4 and make connections therewith and thereby allow the switchboard circuits, the line circuits, and the protective devices, to be tested independently of each other.

I desire it to be understood that the device of this invention may be adapted for 120 use in connection with various circuits and under various conditions. Also that the portions a_4 , p , b_4 , h_3 , i_3 , e , f_3 , d , d_2 , etc., or 125 their equivalents, may be shaped, proportioned and associated with each other as desired, to suitably fulfil the requirements, without departing from the scope of the claims.

I do not wish to limit this invention to 130 the particular details of construction herein set forth, as various modifications thereof may be made or utilized without departing from the scope of the appended claims.

Certain features of the protector herein set forth form the subject-matter of my United States Letters Patent No. 1,288,728, dated Aug 28, 1917, of which this present

5 application is a division.

What I claim as my invention is:

1. An electrical protector having a ground plate comprising a plurality of sheet-metal portions placed together broadsidedly, rows 10 of high-potential electricity arresters on opposite sides of the ground plate along one edge thereof, and spring members carried by the ground plate and holding the arresters against the ground plate, the portions of 15 the ground plate between the arresters being formed outwardly to separate the rows of arresters from each other more than the thickness of the metal of the plate.
2. An electrical protector having a ground 20 plate comprising a plurality of sheet-metal portions placed together broadsidedly, rows of high-potential electricity arresters on opposite sides of the ground plate along one edge thereof, and spring members carried 25 by the ground plate and holding the arresters against the ground plate, the portions of the ground plate between the arresters being formed outwardly to separate the outer ends of the arresters of the respective 30 rows from each other more than the thickness of the metal of the plate.
3. An electrical protector having a ground plate comprising a plurality of sheet-metal 35 portions arranged substantially parallel and in close proximity to each other, rows of high-potential electricity arresters on opposite sides of the ground plate along one edge thereof, and spring members carried 40 by the ground plate and holding the arresters against the ground plate, the portions of the ground plate between the arresters being spaced from each other to 45 separate the rows of arresters from each other more than the thickness of the metal of the plate.
4. An electrical protector having a ground plate comprising a plurality of sheet-metal 50 portions arranged substantially parallel and in close proximity to each other, rows of high-potential electricity arresters on opposite sides of the ground plate along one edge thereof, and spring members carried by the ground plate and holding the arresters against the ground plate, the portions of the 55 ground plate between the arresters being spaced from each other to separate the outer ends of the arresters of the respective rows from each other more than the thickness of the metal of the plate.
5. An electrical protector having a ground 60 plate comprising sheet-metal portions placed together broadsidedly, and rows of high-potential electricity arresters mounted on opposite sides of the ground plate in close 65 proximity thereto, the portions of the ground

plate between the arresters being formed outwardly to separate the rows of arresters from each other more than the thickness of the metal of the plate.

6. An electrical protector having a ground 70 plate comprising sheet-metal portions placed together broadsidedly, and rows of high-potential electricity arresters mounted on opposite sides of the ground plate in close proximity thereto, the portions of the ground 75 plate between the arresters being formed outwardly to separate the corresponding ends of the arresters of the respective rows from each other more than the thickness of the metal of the plate. 80

7. An electrical protector having a ground plate comprising sheet-metal portions arranged substantially parallel and in close proximity to each other, and rows of high-potential electricity arresters mounted on 85 opposite sides of the ground plate in close proximity thereto, the portions of the ground plate between the arresters being spaced from each other to separate the rows of arresters from each other more than the thickness of the metal of the plate. 90

8. An electrical protector having a ground plate comprising sheet-metal portions arranged substantially parallel and in close proximity to each other, and rows of high-potential electricity arresters mounted on 95 opposite sides of the ground plate in close proximity thereto, the portions of the ground plate between the arresters being spaced from each other to separate the corresponding ends of the arresters of the respective rows from each other more than the thickness of the metal of the plate. 100

9. An electrical protector having a sheet-metal mounting plate, and rows of high-potential electricity arresters mounted on opposite sides of the mounting plate along one edge thereof, the mounting plate being formed to separate the rows of arresters from each other more than the thickness of 110 the metal of the plate. 105

10. An electrical protector having a sheet-metal mounting plate, and rows of high-potential electricity arresters mounted on opposite sides of the mounting plate along one 115 edge thereof, the mounting plate being formed to separate the outer ends of the arresters of the respective rows from each other more than the thickness of the metal of the plate. 120

11. An electrical protector having a sheet-metal mounting plate, and rows of high-potential electricity arresters mounted on opposite sides of the mounting plate, the mounting plate being constructed to separate the rows of arresters from each other more than the thickness of the metal of the plate. 125

12. An electrical protector having a sheet-metal mounting plate, and rows of high-potential electricity arresters mounted on opposite sides of the mounting plate, the mounting plate being constructed to separate the rows of arresters from each other more than the thickness of the metal of the plate. 130

4
5
tential electricity arresters mounted on opposite sides of the mounting plate, the mounting plate being constructed to separate the corresponding ends of the arresters 5 of the respective rows from each other more than the thickness of the metal of the plate.

10
13. An electrical protector having a mounting portion, and rows of high-potential electricity arresters mounted on opposite sides of the mounting portion along one edge thereof, the opposite arresters forming pairs, the mounting portion being constructed to separate the outer ends of the arresters of the respective rows from each other sufficiently to admit the end of a person's finger between the arresters of a pair.

15
14. An electrical protector having a mounting portion, and rows of high-potential electricity arresters mounted on opposite sides of the mounting portion, the opposite arresters forming pairs, the mounting portion being constructed to separate the corresponding ends of the opposing arresters from each other sufficiently to admit the 20 end of a person's finger therebetween.

25
15. An electrical protector having substantially parallel rows of high-potential

electricity arresters, the opposing arresters forming pairs, and means separating the corresponding ends of the opposing arresters from each other sufficiently to admit the end of a person's finger therebetween. 30

16. In an electrical protector, a pair of high-potential electricity arresters arranged substantially parallel and back to back, and means separating the corresponding ends of the arresters from each other sufficiently to admit the end of a person's finger therebetween. 35

17. In an electrical protector, a plurality 40 of high-potential electricity arresters arranged substantially back to back, and means separating the corresponding ends of the arresters from each other sufficiently to admit the end of a person's finger therebetween. 45

As inventor of the foregoing I hereunto subscribe my name, this 12th day of July, 1917.

FREDERICK R. PARKER.
